FREQUENCY MODULATED WAVE DETECTOR

Seymour Hunt, Jackson Heights, N. Y., assignor
to Radio Corporation of America, a corporation
of Delaware

Application February 26, 1941, Serial No. 380,649

5 Claims. (Cl. 250—27)

My present invention relates to detectors of variable frequency waves, and more particularly to detectors of frequency, or phase, modulated carrier waves.

One of the main objects of my present invention is to provide a frequency modulated carrier wave detector which includes a rectifier having a pair of carrier energy input circuits; the input circuits being individually tuned to the carrier frequency and being adapted to develop carrier voltage in phase quadrature relation.

Another important object of the invention is to provide a driver tube for a frequency modulation detector, and one of the carrier-tuned input circuits of the detector being disposed in the cathode circuit of the driver tube.

Another object of the invention is to provide a frequency modulation detector which comprises a single diode having a load resistor in circuit with a pair of tuned circuits reactively coupled to provide phase quadrature relation between the voltages developed thereacross, and one of the tuned circuits being located in the cathode circuit of the preceding limiter tube.

Still other objects of my invention are to improve generally the simplicity and efficiency of frequency modulation detectors, and more especially to provide a detector of such type which is not only reliable, but is economically manufactured and assembled.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 shows a circuit diagram of one embodiment of the invention,

Fig. 2 vectorially shows the functioning of the discriminator section of the detector network,

Fig. 3 illustrates a modification; Fig. 4 is another form.

Referring now to the accompanying drawing, wherein like reference characters in the figures designate similar circuit elements, the numeral 1 indicates a pentode, say of the 6K7 type, acting as an intermediate frequency amplifier. For this purpose the input transformer 2 has its primary and secondary windings each resonated to F_c the center frequency of the frequency modu-

lated carrier waves. Similarly, the output transformer 3 has its primary and secondary winding each tuned to F_c . The receiver being of the superheterodyne type and having its signal selector circuits tunable over the assigned frequency range of 42 to 50 megacycles (mc.), there will be used an I. F. value chosen from a range of 2 to 8 mc. For example, a value of 4.3 mc. may be used for the I. F. magnitude. Hence, F_c will be 4.3 mc.

The usual tunable radio frequency amplifier may precede the converter stage whose output circuit is adjusted to deliver I. F. energy to transformer 2 of the desired F_c value. As is well known, the audio modulation appears in the frequency modulated carrier wave as a carrier frequency deviation. The audio amplitude variation corresponds to carrier frequency deviation from F_c , while the audio frequencies per se correspond to the rate of deviation from F_c . Since a purely frequency-variable carrier wave must be delivered to the detector input, or discriminator, network, a carrier amplitude variation limiter is used prior to the detector. Noise impulses, prior resonant circuits and fading will each cause amplitude variation effects to appear in the frequency-variable carrier. The limiter acts to eliminate the amplitude variation so as to insure delivery of a constant amplitude-frequency variable carrier to the discriminator.

The tube 4, which may be of the 6R7 type, has a cathode 5, a control grid 6 and a plate 7. Adjacent cathode 5 is arranged an auxiliary anode 8. The grid 6 is connected to the high potential side of the input circuit, while resistor 9, shunted by I. F. bypass condenser 10, is connected between the low potential side of the input circuit and ground. The plate 7 is connected to a source of positive direct current potential through resistor 11, each end of the latter being bypassed to ground by a capacity.

The cathode 5 is connected to ground through coil 12 of tuned circuit 12—13 resonated to F_c . The anode 8 is connected to ground through a series path comprising coil 14 and load resistor 16. The coil 14 is shunted by condenser 15, and is tuned to the value of F_c . Coils 12 and 14 are magnetically coupled. Load resistor 16 is bypassed for I. F. currents by condenser 16'. The audio, or modulation, voltage developed across resistor 16 is taken off through audio bypass condenser 17.

Considering, first, the limiter section of tube 4, it is pointed out that rectification takes place in the grid circuit of tube 4, and a direct current

voltage is built up across the network 9-10. This voltage biases the grid 6, and tends to limit the plate current flow. Resistor 11 in series with the "B" supply to the plate 1 also tends to limit the plate current. In this way there is secured a limitation of carrier amplitude variation. The direct current voltage across 9 may also be used for the usual AVC function. The plate current flows through the coil 12 of the tuned primary circuit 12-13, and develops across circuit 12-13 a radio frequency voltage which is vectorially represented by the symbol E_1 in Fig. 2. A second voltage E_2 is induced in the secondary tuned circuit 14-15 by virtue of the magnetic coupling between coils 12 and 14. In Fig. 2 the voltage E_2 is shown as 90 degrees out of phase with the voltage E_1 . This is the phase relation which exists at the frequency value F_c . Both voltages E_1 and E_2 are rectified by diode 8-5, and the diode current which flows through load resistor 16 is proportional to the vector sum of voltages E_1 and E_2 . In Fig. 2 this vector sum is represented by the dotted arrow E_3 .

As the center frequency F_c of the frequency modulated carrier waves shifts its frequency in relation to the applied modulation the angle between E_1 and E_2 shifts. As the angle shifts the length of vector E_3 increases and decreases. That is, the coupled circuits 12-13 and 14-15 function as a discriminator which converts the frequency-variable carrier into a corresponding carrier of constant frequency but of variable amplitude. Furthermore, the variable amplitude corresponds to the audio modulation applied to the carrier.

In Fig. 3 there is shown the arrangement of Fig. 1 in a balanced rectifier circuit. Tube 4 has two auxiliary anodes 8 and 8' adjacent cathode 5. The midpoint of coil 14 is grounded. The load resistor 16' has a grounded center tap. The anodes 8 and 8' are connected to opposite sides of tuned circuit 14-15 through coupling condensers. Radio frequency chokes are in series with the coupling condensers. The action is similar to that of Fig. 1, except that balanced rectification is secured.

In Fig. 4 there is shown a modification of the arrangement shown in Fig. 1 wherein the rectifier associated with the discriminator is of the balanced type. The midpoint of coil 14 is connected through coil 23 to the junction of resistors 31 and 24, whereas the opposite ends of coil 14 are connected to the anodes respectively of diodes 30 and 20. The load resistor 31 is connected between the anode and cathode of diode 30, and it will be noted that the load resistors 21 and 24 are arranged in series relation. The cathode end of resistor 31 is connected to an audio frequency utilization network through a condenser 40 which has a low impedance to audio frequency voltage. The cathode end of resistor 24 is grounded, and each of load resistors 31 and 24 is by-passed for I. F. The coils 12 and 14 are magnetically coupled as in Fig. 1. In this arrangement a special bias resistor 41, shunted by an I. F. by-pass condenser 42, is arranged in series between the cathode of tube 4 and coil 12. The direct current blocking condenser 41' is connected between the high side of coil 12 and midpoint of coil 14. The operation in this arrangement is similar to that described above. Across circuit 14-15 is developed carrier voltage which is in phase quadrature at F_c with the voltage across 12-13. The voltages across resistors 31 and 24 are in polarity opposition so that at F_c

zero voltage is developed across these load resistors.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In an angular velocity-modulated carrier wave detection system, a tube provided with input and output electrodes, a modulated carrier voltage input circuit connected to the input electrodes, an output circuit tuned to the wave center frequency and common to the said input and output electrodes, a second circuit tuned to said center frequency and reactively coupled to said tuned output circuit whereby carrier voltages across the coupled circuits are in phase quadrature at the center frequency, means for rectifying the carrier voltage across each of the coupled tuned circuits, and means for combining the rectified voltages in polarity opposition.

2. In an angular velocity-modulated carrier wave detection system, a tube provided with input and output electrodes, a modulated carrier voltage input circuit connected to the input electrodes, an output circuit tuned to the wave center frequency and common to the said input and output electrodes, a second circuit tuned to said center frequency and reactively coupled to said tuned output circuit whereby carrier voltages across the coupled circuits are in phase quadrature at the center frequency, a single diode means for rectifying the carrier voltage across each of the coupled tuned circuits, and means for combining the rectified voltages in polarity opposition.

3. In an angular velocity-modulated carrier wave detection system, a tube provided with input and output electrodes, a modulated carrier voltage input circuit connected to the input electrodes, an output circuit tuned to the wave center frequency and common to the said input and output electrodes, a second circuit tuned to said center frequency and reactively coupled to said tuned output circuit whereby carrier voltages across the coupled circuits are in phase quadrature at the center frequency, a single diode means for rectifying the carrier voltage across each of the coupled tuned circuits, and means for combining the rectified voltages in polarity opposition, said last means consisting of a single resistor in series with the coupled tuned circuits.

4. In a frequency modulated carrier wave detection system, a tube provided with input and output electrodes, a modulated carrier voltage input circuit connected to the input electrodes, an output circuit tuned to the carrier wave center frequency and common to the said input and output electrodes, a second circuit tuned to said center frequency and reactively coupled to said tuned output circuit whereby carrier voltages across the coupled circuits are in phase quadrature at the center frequency, means including diode anodes in said tube for rectifying the carrier voltage across each of the coupled tuned circuits, and means for combining the rectified voltages in polarity opposition to derive the modulation voltage.

5. In a phase, or frequency, modulated carrier wave detection system, a tube provided with in-

put and output electrodes, a modulated carrier voltage input circuit tuned to the carrier wave center frequency connected to the input electrodes, an output circuit tuned to the center frequency and common to the said input and output electrodes, a second circuit tuned to said center frequency and reactively coupled to said tuned output circuit whereby carrier voltages

5 across the coupled circuits are in phase quadrature at the center frequency, a pair of opposed rectifiers connected across the second tuned circuit for rectifying the carrier voltage across the second tuned circuit, and means for combining the rectified voltages in polarity opposition thereby to provide the modulation voltage.

SEYMOUR HUNT.
